UNITED STATES PATENT OFFICE.

CHARLES E. BROOKS, OF ST. LOUIS, MISSOURI, ASSIGNOR, BY DIRECT AND MESNE ASSIGNMENTS, TO BROOKS-LATTA AUTOMOBILE MANUFACTURING COMPANY, OF ST. LOUIS, MISSOURI, A CORPORATION OF MISSOURI.

GAS-ENGINE.

1,096,594.

Specification of Letters Patent. Patented May 12, 1914.

Application filed May 23, 1910. Serial No. 562,810.

To all whom it may concern:

Be it known that I, CHARLES E. BROOKS, a citizen of the United States, residing at the city of St. Louis, State of Missouri, have 5 invented a new and useful Gas-Engine, of which the following is a specification.

This invention relates to gas engines, and it has for an object to arrange in operative combination a piston chamber and piston, 10 a pump or supply device for supplying the gas to the piston chamber, and a valve device controlling the supply of gas to the pump, and from the pump into the piston chamber.

Another object is to produce an improved 15 gas engine and equip the same with devices which are operable effectively to flush the piston chamber, after each explosion, with a charge of fresh air which will carry out 20 all products of the combustion and explosion, and in this way keep the engine clean and cool.

A further object is to produce an improved 25 gas engine comprising operating pistons, pumps arranged to compress and supply gas to the pistons, and valves operable to control the supply of gas to the pumps and to the pistons, in combination with a shaft driven or rotated by said pistons, and crank 30 or equivalent connections whereby said shaft will operate said pumps and said valves, thus obviating the use of springs, cam shafts, auxiliary valves, etc., which are so common and undesirable in gas engines 35 of usual construction.

There are other objects to be attained by 40 this invention all of which will be apparent to those skilled in the art to which this invention relates, and which also become obvious from a reading of the following description of the invention, reference being 45 made to the accompanying drawings in which—

Figure 1 is a vertical sectional view of the 45 engine, showing the working cylinders and pistons and pumping cylinders and piston, and their connections to the crank shaft of a two battery engine. Fig. 2 is a horizontal sectional view on a line such as $a-a$ of Fig. 50 1. Fig. 3 is a vertical sectional view through the piston chamber and valve chamber approximately on the line $b-b$ of Fig. 2. Fig. 4 is an inner side view of the valve chamber or housing detached from the

engine. Fig. 5 is a view of the upper end 55 thereof. Fig. 6 is a sectional view of the valve in a position to admit gas into the pumping cylinder and compressed air into the piston cylinder, as in starting the engine. Fig. 6^a is a diagrammatic view which 60 shows the axis of the crank shaft in section, and by appropriate circles shows the position of the cranks or eccentrics which operate the pump, the piston, and the valve for one of the engine units. Fig. 7 is a sectional view of the valve in an advanced 65 position closing the air inlet port to the piston cylinder, but still admitting gas into the pump, and about to open the exhaust port. Fig. 7^a is a diagrammatic view of the crank 70 shaft showing its position when the valve, the piston, etc., are in the position shown in Fig. 7. Fig. 8 is a sectional view of the valve in the position closing the gas inlet port to the pump, and in position admitting 75 a charge of fresh air from the crank case into the piston cylinder to flush and clean said cylinder, the exhaust port from the working cylinder being still open. Fig. 8^a shows the position of the crank shaft when 80 the parts occupy the position shown in Fig. 8. Fig. 9 is a sectional view of the valve admitting gas from the pump into the piston cylinder and admitting a supply of 85 fresh air into the crank shaft case and closing the exhaust port from the working cylinder. Fig. 9^a is a diagrammatic view of the crank shaft when the engine is operating in the position shown in Fig. 9. Fig. 10 is a sectional view of one of the valves when 90 all ports therethrough are closed, the exhaust port from the piston cylinder being closed by the piston. Fig. 10^a is a diagrammatic view of the crank shaft when the engine is operating as shown in Fig. 10. Fig. 95 11 is an enlarged sectional view of the valve similar to Fig. 6 and constitutes a convenient reference for the views shown in Figs. 12 to 16, inclusive. Fig. 12 is a cross sectional view on the line $c-c$ of Fig. 11. Fig. 13 is a cross sectional view on the line $d-d$ of Fig. 11. Fig. 14 is a cross sectional view on the line $e-e$ of Fig. 11. Fig. 15 is a sectional view on the line $f-f$ of Fig. 11. Fig. 16 is a transverse sectional view on the 105 line $g-g$ of Fig. 11. Fig. 17 is a view of a part of the working piston cylinder, showing the exhaust port from the cylinder and

the bridging for said port. Fig. 18 is a sectional view on the line $h-h$ of Fig. 14, showing the inlet from the carbureter (or gas supply source) and the port through the 5 valve for conducting the gas to the pump.

In mentioning vertical and horizontal positions of the engine I do not limit myself to such adjustments, since the engine may be mounted in other positions. The vertical 10 position is that in which the pistons operate vertically, and the horizontal position is that in which the pistons move in a horizontal plane. I prefer to operate the pistons vertically.

15 In the drawings I have illustrated an engine having two working pistons. The pump and valve for each working piston are operable to admit a charge of gas to the piston cylinder at each upward stroke of the piston, and the gas thus admitted is compressed by the piston and is exploded at the time the working piston completes its upward stroke; and this operation is thereafter automatically performed at each upward stroke of each working piston. The flushing or scavenging of the working piston cylinders is performed while the working pistons are completing their downward strokes by an inrush of compressed air from the crank shaft chamber, and this operation is performed in each working piston cylinder at each downward stroke of the piston. The efficient and satisfactory operation of the engine in this way is another object to 35 be attained by this invention.

In the embodiment illustrated the engine casing contains one or more working piston cylinders 1, and a pump cylinder or chamber 2 for each working piston cylinder. 40 The casing also contains a chamber 3 through which the crank shaft extends, and which may be referred to as the crank shaft case. The crank shaft 4 is journaled in bearings in the case as shown in Fig. 1, and 45 may be connected with the driven mechanism by any suitable power transmission devices (not shown). A piston 5 is mounted in each working piston cylinder and has a connection 6 to an appropriate crank 7 on 50 the crank shaft 4 whereby operation of the pistons will rotate said shaft. The pump pistons 8 are connected to cranks 9 by suitable connections 10, so that the pump pistons will be operated by the crank shaft. 55 The cranks 9 are arranged at right angles to the cranks 7, the said cranks 9 being ninety degrees in advance of the corresponding cranks 7, which keeps the working pistons one half stroke behind the pump pistons. The valve casings or housings 11, are bolted onto the engine case, as shown in Fig. 2, fitting against the surfaces of the piston cylinders and the pump cylinders. A water jacket 12 surrounds the cylinders, and 60 is continuous across the valve cases or hous- 65

ings, as illustrated. Through the valve cases the different ports open. The port 13 (Fig. 3) communicates with a compressed air storage tank, and the admission of air therethrough is controlled by well known 70 devices (not shown) and is utilized for starting the engine. The port 14 admits the gas. The port 15 is the exhaust outlet for the products of explosive combustion, and the port 16 (Figs. 6 to 11) is an inlet 75 port for admitting supplies of fresh air into the crank shaft case, from which the air is admitted into the working piston cylinder to flush and cool the same.

Within the valve case the valve 17 operates, said valve being preferably cylindrical in form. As previously stated a single valve is provided for the pump cylinder and the piston cylinder, said valve being provided with appropriate passages or ports for all 80 purposes. The port 18 (Figs. 6 and 11) in idle position of the engine registers with the air admission port 13 which admits air from the storage tank. A passage 19 leads into the piston chamber and is in the form 85 of a narrow slot through the cylinder wall, so that the air will be injected in the form of a cooling jet. The valve is connected with an eccentric 20 on the crank shaft by an encircling ring or strap 21 and a connection 22, so that the valve also will be operated by the crank shaft. A passage 23 in the valve constantly receives gas from the inlet 14 and leads to an opening 24 into the pump cylinder. The compressed air entering the 90 piston cylinder through the inlet passage 13, 18 and 19 starts the engine, as stated above, and moves the valve 17 downwardly to its lowest position, shown in Fig. 9, in which a port 25 in the valve registers with 95 the openings 19 and 24 and admits the gas from the pump cylinder into the piston cylinder. This passage of the gas from the pump to the piston cylinder occurs during the upward stroke of the pump piston 8 and 100 about the time that the working piston 5 starts on its upward movement, as shown in Fig. 9. The gas inlet passage 25 is then quickly closed by the action of the eccentric moving the valve, as illustrated in Fig. 10, 105 and the upward movement of the working piston compresses the gas until the explosion is effected through the medium of a well known spark device 26 (Fig. 1). The throttle or valve (not shown) controlling the air 110 inlet passage 18 having been closed the engine will be kept in operation by successive 115 explosions, of which one takes place at the end of each upward stroke of the working piston, the new charge of gas being admitted 120 when the working piston is down to the position shown in Fig. 9. A passage 27 in the valve is arranged to communicate with the air inlet 16 (Fig. 9) and admit fresh 125 air into the crank shaft case where it will 130

be compressed by the action of the pump and working pistons, and at the time the working piston is in its lowest position said passage communicates with a passage 28 into the working piston cylinder (Fig. 8) so as to admit fresh air into said cylinder to flush, clean and cool the same by carrying off the products of the explosive combustion. The air so admitted exhausts through an opening 29, a passage 30 in the valve, and the exhaust port 15. This exhaust takes place during the inrush of air through the passage 27, as may be seen in Fig. 8, in which air is entering through the passage 27—28. The port 29 has oblique bridges 31 (Figs. 16 and 17) which prevent the packing rings on the piston from becoming fouled by contact with the edges of the opening.

20 The diagrammatic views Figs. 6^a, 7^a, 8^a, 9^a, and 10^a illustrate the operation and position of the cranks and eccentrics on the crank shaft by which the working piston, the pump, and the valve are operated. The circle W P represents the crank for the working piston. In Fig. 6 the working piston is in its highest position, and in moving to the position shown in Fig. 7 drives the crank W P from the position shown in Fig. 6^a to the position shown in Fig. 7^a. The further action of the working piston on the crank is illustrated and readily traced in Figs. 8^a, 9^a, and 10^a.

25 The pump crank is indicated in these views by the letters P C. When the working piston is in either its highest position, or in its lowest position the pump piston is midway of a stroke, as shown in Figs. 1 and 6, and its crank is in the position shown in Fig. 6^a. The various positions of the pump and its crank are shown in these diagrammatic views. The valve eccentric is represented by the circle V which will be seen to correspond to the position of the valve as shown in the detail views.

30 I am aware that there may be many alterations and changes from the construction herein shown and described without the least departure from the spirit and scope of the invention. I do not restrict myself to the specific arrangement shown, nor to the use of the engine for any single purpose for it is quite apparent and I am aware that it may be utilized for many purposes. It is particularly adapted for use on automobiles, and for the propulsion of other vehicles, vessels etc., and I have anticipated its use for such purposes.

Having described my invention what I 35 claim and desire to secure by Letters Patent is—

1. In a gas engine, a piston cylinder, a pump cylinder parallel with said piston cylinder, a valve case, a passage from said pump cylinder into said valve case, a pas-

sage from said valve case into said piston cylinder, a valve in said valve case, a passage in said valve, means for moving said valve parallel with said cylinders effectively to register the said passage therein with the two first-named passages, thereby constituting a continuous gas passage from said pump cylinder to said piston cylinder, an air inlet to said piston cylinder controlled by said valve, and an exhaust outlet from said piston cylinder controlled by said valve, substantially as specified.

2. In a gas engine, a piston cylinder, a piston in said cylinder, a valve, means for moving said valve parallel with the movement of said piston whenever said piston operates, and an air inlet passage, a gas inlet passage, and exhaust passage, all through the wall of the piston cylinder and all controlled by said valve, substantially as specified.

3. In a gas engine, a piston cylinder, a piston in said cylinder, a shaft driven by said piston, a gas inlet through the wall of said cylinder, a fresh air inlet through the wall of said cylinder, an exhaust outlet through the wall of said cylinder, a valve case against the wall of said cylinder and having passages communicating with said inlets and said outlet, a valve in said case, and means connecting said valve with said shaft whereby said valve will be moved parallel with said cylinder effectively to open and close said inlets and said outlet during operation of the engine, substantially as specified.

4. In a gas engine, a piston cylinder, a piston in said cylinder, a crank-shaft case, a crank-shaft journaled in bearings in said case, a valve arranged to operate parallel with said piston having a passage for admitting gas into the piston cylinder and another passage for admitting air into said crank-shaft case and from said crank-shaft case into said piston cylinder, and a link and eccentric constituting a connection between said crank-shaft and said valve, whereby said valve will be operated effectively to control the admission of gas into said piston cylinder, the admission of air into said crank-shaft case and from said crank-shaft case to said piston cylinder, substantially as specified.

5. In a gas engine, a piston cylinder, a piston in said cylinder, a crank-shaft case, a crank-shaft journaled in bearings in said crank-shaft case and being operated by said piston, a valve having one passage to admit gas to said piston cylinder and another passage to admit air to said crank-shaft case and from said crank-shaft case to said piston cylinder, a case inclosing said valve and provided with openings for said passages and means connecting said valve with said crank-shaft whereby said crank-shaft 120

- will operate said valve effectively to open and close said passages, substantially as described.
6. In a gas engine, a piston cylinder, a piston in said cylinder, an air inlet to said cylinder for admitting compressed air to start the engine, a pump cylinder, gas inlet to said pump cylinder, a passage for conveying gas from said pump cylinder to said piston cylinder, an exhaust outlet from said piston cylinder, a crank-shaft case for said cylinders, a passage for admitting air to said crank-shaft case, a passage for admitting air from said crank-shaft case to said piston cylinder, and a single valve controlling all of said inlets, said exhaust outlet and the admission of air into said crank-shaft case and from said crank-shaft case into said piston cylinder, substantially as specified.
7. In a gas engine, a piston cylinder, a piston in said cylinder, an air inlet to said cylinder for admitting compressed air to start the engine, a pump cylinder, a gas inlet to said pump cylinder, a passage for conveying gas from said pump cylinder to said piston cylinder, an exhaust outlet from said piston cylinder, a crank-shaft case for said cylinders, an inlet for admitting air into said crank-shaft case, a crank-shaft journaled in bearings in said crank-shaft case, a single valve operable to control all of said inlets and an outlet, a passage delivering air from said crank-shaft case to said piston cylinder and controlled by said valve, and a connection from said crank-shaft for operating said valve, substantially as specified.
8. In an engine, a pump cylinder, a piston in said cylinder, a piston cylinder parallel with said pump cylinder, a piston in said cylinder, a valve arranged to operate parallel with said cylinders and having a passage communicating between said pump cylinder and said piston cylinder and another passage arranged to admit fresh air into said piston cylinder, a crank-shaft connected to the piston in said piston cylinder, connections whereby said crank-shaft will operate said pump piston and valve parallel with each other effectively to force a fresh supply of gas into said piston cylinder at the return stroke of the said pump piston, and an exhaust outlet from said piston cylinder controlled by said valve, substantially as specified.
9. In an engine, a pump cylinder, a piston in said cylinder, a piston cylinder parallel with said pump cylinder, a piston in said piston cylinder, a valve arranged to operate parallel with said cylinders and pistons and having a passage communicating between said pump cylinder and said piston cylinder and another passage arranged to admit fresh air into said piston cylinder,
- a crank-shaft driven by said last-named piston, and connections between said crank-shaft and said pump piston and said valve whereby said crank-shaft will operate said pump piston and said valve parallel with each other effectively to force a fresh supply of gas into the said piston cylinder at the return stroke of the piston in said pump, substantially as specified.
10. In a gas engine, a piston cylinder, a pump cylinder parallel with said piston cylinder, a valve case, a passage from said pump cylinder into said valve case, a passage from said valve-case into said piston cylinder, a valve in said valve-case, a passage in said valve, means for moving said valve parallel with said cylinders effectively to register the said passage therein with the two first-named passages, thereby constituting a continuous gas passage from said pump cylinder to said piston cylinder, and an air inlet to said piston cylinder controlled by said valve, substantially as specified.
11. In a gas engine, a piston cylinder, a pump cylinder parallel with said piston cylinder, a valve case, a passage from said pump cylinder into said valve case, a passage from said valve-case into said piston cylinder, a valve in said valve-case, a passage in said valve, means for moving said valve parallel with said cylinders effectively to register the said passage therein with the two first-named passages, thereby constituting a continuous gas passage from said pump cylinder to said piston cylinder, and an exhaust outlet from said piston cylinder controlled by said valve, substantially as specified.
12. In a gas engine, a piston cylinder, a pump cylinder, a crank-shaft case for said cylinders, a valve case, a gas passage from said pump cylinder into said valve case, a gas passage from said valve-case into said piston cylinder, a passage for admitting fresh air into said crank-shaft case, a passage for admitting air from said crank-shaft case into said piston cylinder, a valve in said valve-case, a passage in said valve, means for moving said valve parallel with said cylinders effectively to register the said passage therein with the two first-named passages, and a passage in said valve arranged to register with the passage to said crank-shaft case and thereafter with the passage for admitting fresh air to the piston cylinder, substantially as described.
13. In a gas engine, a piston cylinder, a pump cylinder, a crank-shaft case for said cylinders, a valve case, a passage from said pump cylinder into said valve case, a passage from said valve-case into said piston cylinder, a passage for admitting fresh air into said crank-shaft case, a passage for admitting air from said crank-shaft case into said piston cylinder, a valve in said valve-case,

case, a passage in said valve, means for moving said valve parallel with said cylinders effectively to register the said passage therein with the two first-named 5 passages, and a passage in said valve arranged to register with the passage to said crank-shaft case and thereafter with the passage for admitting fresh air to the piston cylinder, and an exhaust outlet from said piston cylinder controlled by said valve, substantially as specified.

14. In a gas engine, a piston cylinder, a piston in said cylinder, a crank-shaft case for said cylinder, a valve-case, a passage 15 from external atmosphere into said valve-case, a valve in said valve-case, a passage in said valve adapted to register with said passage into said valve-case so as to constitute a continuous passage whereby air may be 20 conducted into said crank-shaft case, a passage from said valve case into said piston cylinder, means whereby said valve will be operated so as to admit air into said crank-shaft case when said piston is at one end of 25 a stroke and will admit air into said piston cylinder when said piston is at the other end of a stroke, and an exhaust outlet from said piston cylinder controlled by said valve, substantially as described.

15. In a gas engine, a crank-shaft case, a pump cylinder opening into said case, a piston in said pump cylinder, a piston cylinder opening into said case, a piston in said cylinder, a valve-case, a valve in said case, a passage 35 in said valve-case, a passage in said valve adapted to register with said first-named passage and thereby constitute a continuous passage to admit air into said crank-shaft case, connections whereby said 40 valve will be operated effectively to admit air through said continuous passage when one of said pistons is near the end of its stroke away from said crank-shaft case, and a passage controlled by said valve for delivering gas from 45 said pump cylinder to said piston cylinder, substantially as described.

16. In a gas engine, a crank-shaft case, a pump cylinder opening into said case, a piston in said pump cylinder, a piston cylinder 50 opening into said case, a piston in said cylinder, a valve-case, a passage into said valve-case, a valve in said valve-case, a passage in said valve, connections for operating said valve effectively to register said passage 55 therein with the said passage in the said valve-case to admit air into said crank-shaft case when one of said pistons is near the end of its stroke away from said case, a passage from said valve-case to said piston cylinder whereby air may be admitted from said crank-shaft case into said piston cylinder when the piston in said 60 piston cylinder is near the end of its stroke toward said crank-shaft case, and a gas passage from said pump cylinder to said piston cylinder con-

trolled by said valve, substantially as described.

17. In a gas engine, a crank-shaft case, a pump cylinder opening into said case, a piston in said pump cylinder, a piston cylinder 70 opening into said case, a piston in said piston cylinder, a valve-case, a passage into said valve-case, a valve in said valve-case, a passage into said valve, connections for operating said valve effectively to register said 75 passage therein with the said passage in the said valve-case to admit air into said crank-shaft case when one of said pistons is near the end of its stroke away from said crank-shaft case, a passage from said valve-case 80 into said piston cylinder whereby air may be admitted from said crank-shaft case into said piston cylinder when the piston in said piston cylinder is near the end of its stroke toward said crank-shaft case, and an exhaust outlet from said piston cylinder controlled by said valve, substantially as specified.

18. In a gas engine, a crank-shaft case, a pump cylinder opening into said case, a piston in said pump cylinder, a piston cylinder opening into said case, a piston in said piston cylinder, a valve-case, a passage into said valve-case, a valve in said valve-case, a passage in said valve, connections for operating said valve effectively to register said 90 passage therein with the said passage in the said valve-case to admit air into said crank-shaft case when one of said pistons is near the end of its stroke away from said crank-shaft case, a passage from said valve-case 95 into said piston cylinder whereby air will be admitted from said crank-shaft case into said piston cylinder when the piston in said piston cylinder is near the end of its stroke toward said crank-shaft case, a passage controlled by said valve for delivering gas from 100 said pump cylinder to said piston cylinder, and an exhaust outlet from said piston cylinder into and through said valve-case arranged to permit exhaust of the products of 105 explosion, substantially as specified.

19. In a gas engine, a piston cylinder, a pump cylinder parallel with said piston cylinder, a piston in each of said cylinders, 115 a valve case attached to said cylinders, a valve in said valve case arranged to operate parallel with said cylinders and said pistons, a gas passage from said pump cylinder to said piston cylinder, a crank-shaft 120 case for said cylinders, an air inlet to said crank-shaft case, an air inlet for admitting air from said crank-shaft case to said piston cylinder, a crank-shaft driven by the piston in the piston cylinder, an eccentric on said shaft, and a connection from said eccentric whereby said valve will be operated parallel 125 with said cylinders and said piston effectively to open and close said gas passage and said air inlets, substantially as specified. 130

20. In a gas engine, a piston cylinder, a pump cylinder parallel with said piston cylinder, a piston in each of said cylinders, a valve case attached to said cylinders, a valve in said valve case arranged to operate parallel with said cylinders and said pistons, a gas passage from said pump cylinder to said piston cylinder, a crank-shaft case for said cylinders, an air inlet to said crank-shaft case, an air inlet for admitting air from said crank-shaft case to said piston cylinder, a crank-shaft driven by the piston in the piston cylinder, an eccentric on said shaft, a connection from said eccentric whereby said valve will be operated parallel with said pistons and said cylinders effectively to open and close said gas passage and said air inlets, and an exhaust outlet from said piston cylinder controlled by said valve, substantially as specified.
21. In a gas engine, a piston cylinder, a pump cylinder parallel with said piston cylinder, a piston in each of said cylinders, a valve case attached to said cylinders, a valve in said valve case arranged to operate parallel with said cylinders and said pistons, a gas passage from said pump cylinder to said piston cylinders, a crank-shaft case for said cylinders, an air inlet to said crank-shaft case, an air inlet for admitting air from said crank-shaft case to said piston cylinder, a crank-shaft driven by the piston in the piston cylinder, an eccentric on said shaft, a connection from said eccentric whereby said valve will be operated parallel with said cylinders and said pistons effectively to open and close said gas passage and air inlets, an exhaust outlet from said piston cylinder controlled by said valve, and a water jacket inclosing said cylinders and also said valve case, substantially as specified.
22. In a gas engine, a crank-shaft case, a valve controlling the admission of air into said case, a piston cylinder, a piston in said cylinder operating effectively to compress air admitted into said case by said valve, an air inlet from said case to said piston cylinder opened by said valve, an exhaust outlet from said piston cylinder opened by said valve when said inlet is opened, a gas passage to said piston cylinder opened by said valve when said outlet is closed, and a pump device operating to force gas through said passage, substantially as specified.
23. In a gas engine, parallel piston and pump cylinders, a piston in each of said cylinders, a passage from the pump cylinder to the piston cylinder, an air inlet to the piston cylinder, an exhaust outlet from said piston cylinder, a valve case parallel with said cylinders, a valve in said case and operating parallel with said cylinders effectively to control said passage, said air inlet, and said exhaust outlet, and a continuous water jacket inclosing said cylinders and also said valve case, substantially as specified.
24. In a gas engine, a piston cylinder, a fresh air inlet to said cylinder, and exhaust outlet from said cylinder, a working piston in said cylinder, a pump cylinder, a gas inlet to said pump cylinder, a passage from said pump cylinder to said piston cylinder, a piston in said pump cylinder driven by said working piston parallel therewith, and a single valve driven parallel with said pistons effectively to control the admission of gas into and from said pump cylinder to said piston cylinder, and also to control admission of fresh air to said piston cylinder and exhaust therefrom, substantially as specified.
- In witness whereof, I have signed this specification in the presence of two subscribing witnesses.
